FILLING MACHINE

Louis A. Boylan, Chicago, Ill.

Application October 22, 1943, Serial No. 507,231

9 Claims. (Cl. 226—109)

In the filling of packages, especially with powdered material, considerable difficulty has been experienced in that air will be carried into the receptacle or package, with the material, with the result that the quantities in the different packages will be unequal and the material will not be satisfactorily packed.

Heretofore, it has been possible to remove only a portion of such air, for the reason, among other things, that the material, as it enters the receptacle, will pack and prevent the air that is intermingled therewith from escaping.

It is one of the objects of the present invention to overcome these difficulties and objections, and to provide improved means whereby the container and the material, as it is deposited thereinto, will be given rapid rotation, subjecting the material to the action of centrifugal force, and thereby separating the air from the material and conveying it away through a suitable conduit.

A further object is to provide improved means for maintaining a collapsible container against collapsing as the air is being exhausted from the inside of the container.

A further object is to provide improved means whereby the container will be arrested in its rotation, at the completion of the filling cycle of operation of the machine.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention, and in which

Fig. 1 is a front elevation of a machine of this character, constructed in accordance with the principles of this invention.

Fig. 2 is a rear elevation of the machine.

Fig. 3 is a view taken from the right-hand side of Fig. 1.

Fig. 4 is a horizontal view, partly in elevation, partly in section, and partly broken away, as taken on line 4—4, Fig. 1.

Fig. 5 is a detail sectional view, on an enlarged scale, taken on line 5—5, Fig. 3.

Fig. 6 is a side elevation of Fig. 5.

Fig. 7 is a detail elevation of a switch operating lever, as taken on line 7—7, Fig. 1.

Fig. 8 is an enlarged vertical sectional view of the filling head, and a portion of the operating mechanism therefor.

Fig. 9 is an enlarged detail sectional view, taken on line 9—9, Fig. 4.

Fig. 10 is a detail sectional view, on an enlarged scale, taken on line 10—10, Fig. 2, and also from the left-hand side of Fig. 9.

Fig. 11 is an enlarged detail sectional view, taken on line 11—11, Fig. 9.

Fig. 12 is an enlarged detail sectional view, taken on line 12—12, Fig. 9.

Fig. 13 is an enlarged detail sectional view, taken on line 13—13, Fig. 9.

Fig. 14 is a wiring diagram.

Referring more particularly to the drawings, the numeral 20 designates a suitable supporting structure, and mounted thereupon is a vertically movable shaft 21 provided with a passage 22 therethrough, and the shaft is preferably mounted in suitable bearings 23, and has removably supported upon the end thereof a platform or holder 24, for the package. This platform 24 is secured to the end of the shaft 21 in any suitable manner, preferably by being provided with a bifurcated portion 25, into which a pin 26 projects, so that when the shaft 21 is rotated, the platform 24 will also be rotated. This platform is provided with an opening 27 therethrough, which registers with the opening 22 in the shaft 21, for a purpose to be hereinafter described. The platform is provided with a recess 28 within which the package 29 is seated, so that a portion of the package will extend over the opening 27.

30 The shaft 21 is rotated in any suitable manner, such as by means of a pulley 30 over which a belt 31 passes, and this belt in turn passes over a pulley 32 on a drive shaft 33, the latter being rotated by means of a suitable motor 34.

35 The shaft 21 is moved longitudinally so as to raise and lower the same, preferably by means of fluid pressure which is supplied from a suitable source through a pipe 35 and connects with a pressure regulator 36 (see particularly Fig. 1).

40 The pressure regulator, in turn, is connected, by means of a pipe 37, to a combined valve and escape mechanism 38.

Leading from the unit 38 is a pipe 39 that in turn is connected with a cylinder 40 (see particularly Fig. 3), in which a piston 41 reciprocates, and this piston in turn is connected to a piston rod 42 that moves within the cylinder 40. The upper end of the piston rod is connected to a yoke which is preferably in the form of a head 43 and side members 44 that are provided with lateral projections 45 that project and move within a recess 46 in a head 47, the latter being connected to the shaft 21, so that the shaft 21 can rotate with respect to the yoke 44.

45 Leading also from the valve unit 38 is another

pipe 48 that has communication with the cylinder 40 above the piston 41 so that, when a foot pedal 49 is operated, the valve unit 38 will permit fluid pressure to enter the cylinder 40 below the piston 41 to raise the head or platform 24, air above the piston escaping through the pipe 48. When, however, the foot pedal 49 is released, the fluid pressure will operate upon the top of the piston 41 to lower the same, and with it the head 24, the fluid beneath the piston 41 escaping through the pipe 39. The valve and escape unit 38 may be of any desired or suitable construction, to operate in the manner just described.

The pulley 30 (Fig. 5) is splined or keyed upon the shaft 21, as at 50, so as to permit the shaft 21 to be moved longitudinally. The shaft 21, at its lower end, has communication with a chamber 51 that has connected to it a suction pipe 52, for a purpose to be hereinafter described, and as shown more clearly in Fig. 3. The shaft 21 has connection with the chamber 51 in any desired or suitable manner, preferably by means of a joint 53 of any suitable construction which will permit the shaft 21 to rotate with respect to the chamber 51 and, at the same time, maintain a fluid tight joint therebetween.

A slide 54 is mounted upon a support 55, which latter is preferably in the form of a tubular member having a threaded opening in its end 56, into which the threaded end of a shaft 57 projects. This shaft 57 is adapted to be rotated, preferably by means of intermeshing gears 58-59 through the medium of a shaft 60 and a hand-operating device 61. By rotating the shaft 60, the shaft 57 will be rotated, and this in turn will raise and lower the support 55, according to the direction of rotation of the shaft, to adjust the head 24 to accommodate packages of varying sizes.

Carried by the slide 54 is a tubular shaft 62 (see Fig. 8) mounted in suitable bearings 63 and provided with packing 64-65-66, so as to provide fluid tight joints. The shaft 62 is rotated in its bearings, preferably by means of a pulley 67, over which a drive belt 68 passes, and this drive belt in turn also passes over a pulley 69 on the shaft 33. The lower end of the shaft 62 is open, and is preferably reduced, as at 70, and projects through a head 71, the latter being preferably provided with a resilient face 72, preferably in the form of rubber.

The shaft 62 is also provided with one or more passages 73 that also open through the end of the shaft, and extending across the passage 73 is a suitable screen 74, so that the screen will rotate with the shaft 62 and the head 71, and the end 70 of the shaft passes through and beyond the screen to project into the receptacle 29 when the latter is in a position to be filled. The passage 73 communicates with a chamber 75 which in turn has connected and communicating therewith a suction or vacuum pipe 76.

When a package 29 is placed upon the platform 24, and the latter is elevated in the manner already described, the package will move into engagement with the rubber facing 72 of the head 71 to close the package or container. In this position, the end of the shaft 62 will project into and have communication with the inside of the package, as will also the passage 73. Communicating with the shaft 62 is a supply pipe 77 which receives a supply of powdered material from any suitable source, such as from a hopper 78, suitably located.

When the parts are in the position shown in Fig. 8, that is, when the package or container is

closed by the head 71-72, and suction is created in the pipe 76, the air in the package or container 29 will be exhausted through the passage 73. This suction will also operate to draw in the powdered material from the hopper through the pipe 77, and pipe or shaft 62, to be discharged into the package. The screen 74 is of such a size or gauge as not to permit the escape of any of the powdered material through the passage 73. During the time that the powdered material is being fed, in this manner, into the package or container 29, the shaft 21 will be rotated, and this will spin or axially rotate the package, and with it the head 71, so that during the time that the material is being fed into the package, the material will be subjected to the action of centrifugal force, and thereby separate the air from the contents of the package, so that the material will be equally distributed and an equal amount of material will be fed into each package or container.

Suitable mechanism for arresting the rotation or spinning of the container 29 at the end of the filling cycle, will be hereinafter described. Inasmuch as a number of the containers or packages which are being filled are constructed of collapsible material, it will be manifest that, by exhausting the air from the inside of the container, the natural tendency will be to collapse the container or buckle the bottom thereof. This operation is prevented by reason of the fact that, as the material is being supplied to the container and the air is being exhausted therefrom, a suction is being created through the passage 72 in the pipe or shaft 21, and through the chamber 51, by means of the suction created in the pipe 52, as will be described.

If desired, a suitable belt tightener 79 may be provided, which operates upon a belt 80 that passes over a pulley 81 on the shaft 33 and also over a pulley 82 on the shaft of the motor 34, so as to control the tension of the belt and likewise the speed of rotation of the shaft 33. This belt tightener 79 may be of any suitable construction, and is adapted to be actuated by means of a hand-operated device 83.

The cylinder 40 may be supported in any suitable manner, such as by hanger means 84 (see Figs. 1 and 3) to which a suitable frame 85 is connected, and in which frame the yoke 44 and chamber 51 are located, the frame being of a sufficient size to permit the raising and lowering movement of the shaft 21 and the parts connected thereto. The pipe 52, which is connected with the chamber 51, is flexible, so as not to interfere with the reciprocatory movement of the shaft 21.

The suction pipe 76, which is connected with the head of the machine (see particularly Figs. 3 and 8), preferably leads through the support 55, which is hollow, and as the pipe is flexible, it will not interfere with the adjustment of the support 55 by the adjustment mechanism 80, etc., when it is desired to raise and lower the head to compensate packages of different sizes. In such adjustment of the support, it is guided by means of suitable guide-ways 86, as shown more particularly in Fig. 3. The suction pipes 52 and 76 (see particularly Figs. 2 and 4) are preferably connected to a manifold 87, and this manifold in turn is connected, by means of a pipe 88, to a suction tank 89 from which the pipe 76 leads to a vacuum pump, so that during a portion of the cycle of operation of the machine, suction will be created through the pipe 88, manifold 87, pipe 76 leading from the head of the machine, and pipe 52 leading from the chamber 51.

Leading also from the manifold 87 is a second pipe 90 (see also Fig. 9), which may discharge into the atmosphere, so that when the pipe 88 is closed and suction is being created, the pipe 90 will be open to relieve the suction or vacuum created through the pipes 76—52. If desired, an indicating gauge 91 may be provided in connection with the tank 89.

The pipes 88 and 90 are alternately opened and closed during the cycle of operation of the machine, to establish the vacuum or suction through the head and chamber 51 of the machine during the cycle of filling of the package, and to relieve the same. That is, when the pipe 88 is closed, the pipe 90 will be open and the vacuum or suction will be relieved, but when the pipe 90 is closed and the pipe 88 is open, the vacuum or suction will be established. Any suitable mechanism may be provided for opening and closing these two pipes, and as they are preferably flexible, having inherent resiliency, they may be closed by pinching them together. To that end, there may be provided (reference being had to Figs. 9 to 13) suitable adjustable supports 92—93 arranged within a suitable housing 94. The pipe 88 rests upon the support 92, and pivotally mounted adjacent the pipe, as at 95, is a lever 96 having a projection 97, a roller 98 preferably being mounted thereupon. A similar lever 99 having a roller 100 mounted thereupon, is positioned above the pipe 90, and these two levers are preferably moved in one direction by the inherent resiliency and action of the respective pipes 88—90.

A shaft 101 is rotatably supported within the framework 94, and secured to this shaft for rotation therewith, are two cams 102—103, the cam 102 being disposed in alignment with the roller 98 on the lever 96, and provided with a projection 104 adapted, when the cam 102 is rotated to engage the roller 98, to rock the lever 96 about its pivot 95 and force the projection 97 against the tube or pipe 88. This, in turn, will force the pipe against the support 92 and contract or pinch the walls of the pipe together so as to close the pipe to the passage of fluid therethrough, as will be seen more clearly in Figs. 9 and 11. Similarly, when the cam 103 rotates, it will force the lever 99 against the pipe 90 to compress, restrict and close this pipe in a similar manner. The cam 103, however, (see particularly Fig. 13) is provided with a cut-away or recessed portion 105, into which the roller 100 on the lever 99 will enter to permit the pipe 90 to expand and open. This cam 103 is so constructed that, during the major portion of rotation of the cam, the periphery thereof will engage the roller 100 to maintain the pipe 90 closed. However, when the recess 105 assumes a position in alignment with the roller 100, the resiliency of the pipe 90 will cause it to expand, and will force the roller 100 into the recess 105 to permit the pipe 90 to open. The cams 102 and 103 are so arranged that they will alternately operate upon the respective controlled pipes; that is, so that when one of the pipes is open, the other will be closed.

Connected to the lever 96 is a switch device 106, which may be of any desired or suitable construction and type, but is preferably a mercury switch which, when in the position shown in Fig. 11, will open the circuit which it controls, but when the pipe 90 expands to open, the switch 106 will be tilted so that the circuit controlled by the switch will be closed, and in this circuit the conductor 107 leads from a power supply line

108 (see wiring diagram) through the switch, and thence through conductor 109 to the motor 34. From the motor 34, the conductor 110 leads back to the other side of the power supply line 111. It will therefore be seen that, by the operation of the switch 106, the suction-operating motor 34 for controlling the spinning of the container as it is being filled, will be controlled.

As a means to control the operation of the cams 102—103 so that they will perform their functions during one cycle of operation, and then be arrested in their movement, a suitable clutch device is provided (reference being had particularly to Figs. 9 to 12), wherein there is provided a suitable drum 112 which is mounted loosely upon the shaft 101, and is continuously rotated.

The drum 112 is driven by means of a sprocket wheel 113 over which a sprocket chain 114 passes, the chain also passing over another sprocket wheel 115 (see particularly Fig. 2), that in turn is driven from a suitable speed reducing mechanism, diagrammatically illustrated at 116 in Fig. 2. The speed reducing mechanism may be actuated by means of a belt 117 that passes over a pulley 118 (see also Fig. 4), to which latter pulley is connected another pulley 119 over which a belt 120 passes, that in turn passes over a pulley 121 on the shaft of a motor 122, the latter being mounted upon a suitable support 123.

Secured to the shaft 101 to rotate therewith, is an arm or support 124, which latter has eccentrically mounted thereupon, and for movement with respect thereto, a friction wheel 125 that projects over the drum 112 and is normally in engagement with the periphery thereof, so as to rotate with the drum and about the axis thereof. This friction roller may be held in contact with the drum in any suitable manner, such as by means of a spring 126, and the roller has connected to it, through the medium of its shaft, an arm 127 which is preferably arranged parallel with the support 124. The arm 127 may be spaced from the support 124 by means of a suitable spacing member 128, if desired.

The operation of this portion of the mechanism is such that, normally, the spring 126 will hold the roller 125 in contact with the drum 112 so as to lock the shaft 101 for rotation with the continuously rotating drum. However, in order to arrest the rotation of the shaft 101 at the end of one complete revolution thereof, it is only necessary to move the roller 125 out of contact with the drum 112, so that the latter will continuously rotate independently with respect thereto, and the shaft 101, with the cams 102—103, will remain idle. For that purpose there may be provided a pin 129 (see particularly Figs. 2 and 3) which is adapted to be moved into the path of rotary movement of the arm 127, to be engaged thereby, so that upon further rotation of the shaft 101 in the same direction, the arm 127 will be rocked against the stress of the spring 126 to rotate the eccentrically mounted roller 125, and move it out of engagement with the periphery of the drum 12.

The movement of the pin 129 is only momentarily; that is, it will move into a position within the path of movement of the arm 127 to rock it, and then will be withdrawn so as to permit the arm to pass, thereby controlling the tubes 88—90. That is, it will close the tube 88 to shut off the vacuum or suction and open the air exhaust at the completion of each cycle of operation of the container, so as to permit the container to be removed and a new one substituted therefor. To

accomplish this operation, the pin 129 is controlled by means of a solenoid 130, to the armature 131 of which the pin is connected. This solenoid is only instantaneously energized, so that after the pin has been withdrawn from the path of movement of the arm 127 to permit the latter to pass, it will be instantly reset into the path of movement of the arm, so that when the arm approaches the pin again, it will be rocked thereby, and the shaft 101 will again be permitted to stop.

The energization of the solenoid 130 is controlled by means of a switch 132 (see particularly Fig. 1, and the wiring diagram), as the supply line 108 is connected to the solenoid on one side and the solenoid is connected by means of the conductor 133 through the switch 132 back to the other side 111 of the supply line. The operating finger or member 134 for the switch may be of any suitable construction, and preferably comprises a body portion, to which a finger 135 (see particularly Fig. 7) is pivotally connected, as at 136, in a position that a portion of the finger 135 will rest against the body portion 134 to prevent its movement about its pivot in one direction, and a spring 137 maintains the finger 135 in this position. The body of the operating member is split, as at 138, so as to be mounted upon a shaft 139 (see also Figs. 5 and 6) that is journaled in the supporting structure 85.

Secured also to the shaft 139 is a gear wheel 140 with which a rack 141, carried by the yoke 44, meshes, so that as the yoke 44 and the shaft 21 are raised to move the platform 24 into a position to hold the container 29 against the head 71-72, the gear 140 and shaft 139 will be rotated, and cause the finger 135 to be rocked across the contact point of the switch 132, thereby instantaneously and momentarily closing the circuit to the solenoid 130 which controls the operation of the pin 129. The finger 135 being pivoted at 136, will yield to pass the contact point of the switch 132 when the shaft 21 and yoke 44 are moved in the opposite direction. The switch 132 may be of any desired or suitable construction to accomplish this purpose. Suffice it to say that it will operate instantaneously and only when the finger 135 wipes thereacross.

The motor 122 is continuously operating so as to continuously rotate the drum 112 of the clutch mechanism, the motor being electrically connected, through the conductors 142-143, with the power supply line, as shown in the wiring diagram.

It is thought that the operation of this apparatus will be clearly understood from the foregoing, but, briefly stated, it is as follows:

When a container 29 which is of a collapsible nature is being filled, the passage-way 27 through the platform or support 24 is allowed to remain open, so that suction will be applied to the outside of the container to hold the bottom from being drawn into the container, or collapsing, and as this suction is relieved at the same time that the suction is relieved when the container is to be opened, the container may be readily removed from the support. However, when a receptacle or container is being filled that is not collapsible, then the passage-way 27 may be closed by a suitable element 27a, such as a washer, which is seated within the tubular portion of the platform that telescopes over the end of the shaft 21 so as to extend across and close both the passage 22 in the shaft 21 and the passage 27.

The motor 122 is continuously operating, and

the shaft 101 is idle, by reason of the pin 129 releasing the clutch mechanism, and the cam 102 will be positioned so as to close the pipe 88, so that there will be no suction therein, while the cam 103 will be in a position to permit the pipe 90 to open to atmosphere. At the same time, the support or platform 24 will be in its lowermost position, so that an operator may place a container upon the platform. As the pipe 88 is closed, there will be no suction at this time in the head of the machine. After the operator has placed the package in position, the foot pedal 49 is depressed so as to permit air to enter the cylinder 40 below the piston 41, to raise the platform 24 until the top of the container contacts the head 71-72 to close the container, and as the facing 72 on the head is of resilient material, a tight seal will be established. This same action causes the "microswitch" 132 to be instantaneously operated as the finger 135 swings across the contact of the switch, due to the rotation of the gear 140 by the rack 141. The solenoid 130 being then energized, will retract the pin 129 from the trip arm 127 of the clutch mechanism, and the shaft 101 then begins to rotate.

During this operation, suction has been created through the pipe 88, as well as the pipe 76, through the various connections, and is manifested within the container 29. This will cause the material to be fed by suction, through the pipes 77-62-70, into the container. The movement of the lever or arm 86, by the expansion of the tube 88, will rock the mercury switch 106, causing the filling head motor 34 to spin the shaft 21 and also the head 71-72, thereby imparting to the contents of the container a centrifugal motion while it is being filled, to separate the air from the material. This will result in an even packing of, and quantity of material within the container.

When the trip clutch 124, 125, etc., makes one complete revolution, it will stop by reason of the position of the pin 129, and the shaft 101 will also stop, with the cams mounted thereupon. The suction will then be shut off through the pipe 88, and communication will be established with the atmosphere through the pipe 90, so that atmospheric pressure will be admitted into the lines, with the result that the suction will be cut off before the container is opened.

The cessation of the rotation of the closed container will indicate to the operator that the filling cycle has been completed. The operator then removes his foot from the foot pedal 49, and the platform 24 together with the container 29, will be lowered away from the head 71-72, thus completing the operation, and the filled package may be removed and replaced with another one to be filled.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. In a filling machine, a support for a container, means for temporarily closing the container, means for thereafter delivering material into the container, means for exhausting air from the container, means for rotating the container while the exhausting means is active, to subject the material to the action of centrifugal force, whereby to separate air from the material, and a screen for preventing entry of the material into

the exhausting means, said screen being rotatable with the container.

2. In a filling machine, a filling head, a container support, a temporary closure for the container carried by said head, means for bringing the container and the closure into and out of co-operating position, means for evacuating the container through said head, means for delivering material into the container, means for spinning the said container to subject the material therein to the action of centrifugal force, whereby to separate air from the material, and a screen for maintaining the evacuating means free of the material in the container, the said screen spinning with the container.

3. In a filling machine, a support for the container, a temporary closure for the container, means for bringing the container and closure in closing co-operation, means for exhausting air from the closed container, means for supplying material into the container, a screen at the entrance end of said exhausting means and separate from the material supplying means, said screen spinning with said container, means for spinning the container as it is being filled, and means responsive to the operation of the first said means for controlling the spinning of the container and also the operation of the air-exhausting means.

4. In a filling machine, a support for the container, a temporary closure for the container, means for bringing the container and closure in closing co-operation, means for exhausting air from the closed container, means for supplying material into the container, means for spinning the container as it is being filled, and means responsive to the operation of the first said means for controlling the spinning of the container and also the operation of the air-exhausting means, the said controlling means embodying a clutch device.

5. In a filling machine, a support for a container, a temporary closure for the container, means for bringing the container and closure in closing co-operation, means for exhausting air from the closed container, means for supplying material into the container, means for spinning the container as it is being filled, means embodying an electric circuit for controlling the spinning of the container, the said air-exhausting means embodying a resilient tubular element, means for contracting the element to close the same to the passage of air therethrough, and means responsive to the operation of the last said means for controlling said electric circuit.

6. In a filling machine, a support for a container, a filling head, means for bringing said head and container into position to close the con-

tainer, a suction passage through the head communicating with the container, a screen supported by the head and extending across the inlet of said suction passage, a material delivery passage discharging into the container through said screen, and means for rotating said container, head and screen, to subject the material in the container to the action of centrifugal force while the air is being exhausted from and the material is being delivered into the container.

7. In a filling machine, a support for a container, a filling head, means for bringing said head and container into position to close the container, a suction passage through the head communicating with the container, a screen supported by the head and extending across the inlet of said suction passage, a material delivery passage discharging into the container through said screen, means for rotating said container, head and screen, to subject the material in the container to the action of centrifugal force while the air is being exhausted from and the material is being delivered into the container, and means for rendering said suction ineffective when the container is opened.

8. In a filling machine, a support for a container, a temporary closure for the container, means for bringing the container and closure in closing co-operation, means for exhausting air from the closed container, means for supplying material to the container, means embodying an electric circuit for spinning the container as it is being filled, one of the said filling and exhausting means embodying a resilient tubular member, means operating automatically at a predetermined time in the cycle of operation of the machine for restricting said resilient tubular member to close the passage therethrough, and a switch device shiftable by the said restricting means for moving the switch device in one direction to control said circuit, the inherent resiliency of said tubular member being operable to move the switch device in another direction.

9. In a filling machine, a filling head, a support for a container, a suction passage through the head communicating with the container, a material delivery passage discharging into the container, a screen for maintaining the material in the container from entering said suction passage, means for rotating said container, head and screen, to subject the material in the container to the action of centrifugal force while the air is being exhausted from, and the material is being delivered into the container, and whereby the screen will be maintained clean from particles of said material.
